UNITED STATES PATENT OFFICE.

HEINRICH SANDNER, OF UNION HILL, NEW JERSEY.

DESIGN FOR A MUSICAL-INSTRUMENT PEDAL.

40,935.

Specification for Design.

Patented Oct. 11, 1910.

Application filed August 18, 1910. Serial No. 577,893. Term of patent 7 years.

To all whom it may concern:

Be it known that I, HEINRICH SANDNER, a citizen of the United States, and a resident of Union Hill, in the county of Hudson and State of New Jersey, have invented a new, original, and ornamental Design for a Musical-Instrument Pedal, of which the following is a full, clear, and exact specification, reference being had to the accompanying drawing, forming a part thereof.

The figure is a perspective view of a pedal showing my new design.

I claim:

The ornamental design for a musical instrument pedal as shown.

HEINRICH SANDNER.
